(57) **CLAIM**

The ornamental design for a combination carabiner calculator, as shown and described.

DESCRIPTION

FIG. 1 is a front, left, top perspective view of a combination carabiner calculator showing my new design;

FIG. 2 is a front elevational view thereof;

FIG. 3 is a rear elevational view thereof, with the broken lines depicting environmental structure and forming no part of the claimed design;

FIG. 4 is a right side elevational view thereof;

FIG. 5 is a left side elevational view thereof;

FIG. 6 is a bottom plan view thereof;

FIG. 7 is a top plan view thereof; and,

FIG. 8 is a front, left, top perspective view thereof, shown in an alternate position of use.

1 Claim, 3 Drawing Sheets
